UNITED STATES PATENT OFFICE

153,413

DESIGN FOR A HAND BRUSH

John G. Baumgartner, Oswego, Ill.

Application April 10, 1948, Serial No. 145,646

Term of patent 14 years

(Cl. D9—2)

To all whom it may concern:

Be it known that I, John G. Baumgartner, a citizen of the United States, residing in the village of Oswego, county of Kane, State of Illinois, have invented a new, original, and ornamental Design for a Hand Brush, of which the following is a specification, reference being had to the accompanying drawings, forming a part thereof, in which:

Fig. 1 is a perspective view of a hand brush showing my new design; and

Fig. 2 is a side elevation thereof.

The end not shown is substantially the same as the end disclosed in Fig. 1.

I claim:

The ornamental design for a hand brush, substantially as shown and described.

JOHN G. BAUMGARTNER.
